UNITED STATES PATENT OFFICE.

MAURICE S. FINCH, OF ST. JOSEPH, MISSOURI, ASSIGNOR TO SPECIALTY SHOE MACHINERY COMPANY, OF ST. JOSEPH, MISSOURI, A CORPORATION OF MISSOURI.

OPERATING MECHANISM FOR SHOE-NAILING MACHINES.

1,182,545.

Specification of Letters Patent.

Patented May 9, 1916.

Application filed April 5, 1915. Serial No. 19,195.

To all whom it may concern:

Be it known that I, MAURICE S. FINCH, a citizen of the United States, residing at St. Joseph, in the county of Buchanan and State 5 of Missouri, have invented certain new and useful Improvements in Operating Mechanism for Shoe-Nailing Machines, of which the following is a specification.

My invention relates to a mechanical 10 movement for actuating the nailing mechanism in shoe machinery and its particular object is to provide suitable interchangeable mechanism whereby the various operations may be performed either by a manually operated foot-lever or by a suitable motor.

An object of my invention is to construct 20 a mechanism that will not, when being operated by one motive power, disturb or actuate the other mechanism which during said operation will remain "dead."

Other objects of my invention are to construct the device in as simple a manner as possible, so that it will be easy to operate and effective in its operation, and which is 25 economical to manufacture.

These objects I prefer to accomplish by the means and in the manner hereinafter 30 fully described and as more particularly pointed out in the claims, reference being had to the accompanying drawings in which a preferred embodiment of my invention is 35 illustrated and in which similar reference characters are employed to designate the same parts in the various figures.

In the drawings: Figure 1 is a vertical 40 side elevation of my invention applied to a shoe-nailing machine, having the adjacent wall of the standard broken away and having the nailing mechanism and anvil removed; Fig. 2 is a similar view showing the 45 relative positions of the parts when the foot lever is depressed; Fig. 3 is a view similar to Fig. 1 showing the relative positions of the parts when actuated through the medium of a motor or power shaft; Fig. 4 is a 50 vertical side elevation of the clutch mechanism for connecting or disconnecting the cam shaft and the motor; Fig. 5 is a fragmentary end elevation of the parts as dis- 55 closed in Fig. 1 of the drawings; Fig. 6 is a detail side elevation of the cam and co- 60 operating mechanism drawn to an enlarged scale, and Fig. 7 is a transverse section there- 65 of taken on line 7—7 of Fig. 6.

Referring to the drawings it will be seen 55 that A represents the usual standard that is preferably a hollow elongated casting of rectangular cross section that is provided with a basal flange B at its lower end and has vertically disposed hollow extensions C and 60 D arising from its upper end in which suitable bearings are provided for the journaling of the upper ends of the main actuating rod or shaft E and anvil rod F. The mechanism for actuating the anvil and anvil rod are 65 fully described and claimed in a co-pending application for Letters Patent of the United States therefor, filed even date herewith (#19,196) and therefore need not be described in the present application. 70

At about its center of height the standard is provided with bearings for a suitable cam-shaft 10 that derives its motion from any suitable source such as a motor or belt and pulley (not shown) through the medium of 75 a drive-shaft 11 and clutch 12. Said clutch may be of any desired type and is adapted to connect or disconnect the aforesaid shafts upon a pull being exerted on connecting rod 13 connected at its upper end to the proper 80 clutch actuating member and at its lower end connected to a foot treadle 14 pivotally fulcrumed upon the wall of said standard A.

The shaft 10 is provided between its bearings with a suitable cam 15 that comprises 85 a circular disk eccentrically mounted thereon and adapted when said shaft is rotated to actuate the main rod or shaft E through the intermediaries hereinafter described. The lower end of rod E terminates in a plane 90 a slight distance above the plane of the horizontal axis of cam shaft 10 and has a substantially rectangular shaped connecting link 16 secured thereto that is provided with a vertically elongated slot 17 in its central 95 portion through which said shaft passes transversely. At its upper end the connecting link 16 is provided with a rounded hollow stub 18 that forms a socket into which the lower end of rod E is adapted to be inserted and secured, while its lower end is provided with a pendent socket 19 into which the upper end of a short rod 20 is likewise inserted and secured. The rod 20 which is reciprocably mounted in a bearing 21 forms 100 practically an extension or continuation of the upper, operating rod E through the medium of their connections with the link 16. 105

Suitable parallel grooved runners 22, are slidably mounted upon the longitudinal vertical side edges or tenons of the link 16 and are connected across the face of said link by horizontally disposed relatively wide strips 23 and 24 that respectively connect the upper and lower ends of said runners and afford bearing surfaces engaged by the cam 15.

A suitable substantially inverted U-shaped cross-arm 25 is bolted transversely to the pendent socket 19 and the outer ends of the arms of the same are connected by means of coiled contraction springs 26 to pins 27 projecting laterally from the upper ends of runners 22. The tension of the springs 26 causes the cross arm 25 and link 16 to be kept normally pulled upwardly to the limit of its movement so that the lateral lug 28 bears against the underside of cross strip 24. When the shaft 10 is rotated cam 15 will engage the upper surface of said cross-strip 24 and move the entire mechanism downwardly as illustrated in Fig. 3 of the drawings. Upon the upward movement of the cam the underside of strip 23 will be engaged thereby and the entire mechanism will be lifted, the result of which is that the rod E is reciprocated sufficiently to operate the nailing and other elements upon the upper end thereof.

In the use of this machine it may not always be found desirable nor convenient to employ motive power to operate it and to take care of such contingency I have provided means for operating the mechanism manually as by a foot lever. To this end I have shown a suitable lever or treadle 30 pivoted at one end between suitable ears 31 on the lower portion of the standard and having its opposite end extended through a slotted opening 32 in said standard. Said lever is kept normally at the upper end of its movement by a coiled contraction spring 33 that is connected thereto at one end and has its opposite end secured to the adjacent wall of the standard. This lever preferably passes transversely across the standard immediately below and in alinement with rod 20 and in axial alinement with said rod it is provided with an elongated vertical slot 34. Suitable parallel links 35 have their upper ends connected to said rod 20 and their lower ends are connected together by a cross pin 36 that passes through the slot 34 in said lever 30 and when in normal position said pin will be in engagement with the upper end of said slot. When the mechanism is operating from motive power and the cam forces the parts downwardly the pin 36 connecting the links 35 will move downwardly in the slot 34 toward the lower end thereof and will move to its normal position when the reverse movement takes place. However, when the machine is operated manually the depression of the foot lever will pull short rod 20, link 16

and rod E downwardly against the tension of springs 26, and shaft 10 being stationary the slot 17 in the link will permit the latter to move downwardly a distance corresponding with the movement given said parts when actuated by the cam and be drawn back to normal position by the springs 26.

Having thus described my invention what I claim as new and desire to secure by Letters Patent, is:—

1. A mechanical movement comprising a longitudinally reciprocable member, a cam shaft adapted to reciprocate said member, a device slidably mounted upon said reciprocable members, means operatively connecting said slide and reciprocable member, and a cam on said shaft adapted to engage said means.

2. A mechanical movement comprising a rotatable drive shaft, a longitudinally reciprocable member provided with an elongated slot through which said shaft extends, a slide on said member provided with laterally disposed flanges, a cam on said shaft adapted to engage said flanges, and means for operatively connecting said slide with said reciprocable member.

3. A mechanical movement comprising a rotatable drive shaft, a longitudinally reciprocable member provided with an elongated slot through which said shaft extends, a slide on said member provided with laterally disposed flanges, a cam on said shaft adapted to engage said flanges, means for operatively connecting said slide with said reciprocable member, and devices that permit the reciprocation of said member independent of said slide.

4. A mechanical movement comprising a rotatable drive-shaft, a longitudinally reciprocable member having an elongated slot therein through which said shaft extends, a slide mounted on said member and provided with substantially horizontally disposed spaced cross-pieces, a cam on said shaft adapted to engage said cross-pieces, and means for operatively connecting said slide and said reciprocable member.

5. A mechanical movement comprising a rotatable drive-shaft, a longitudinally reciprocable member having an elongated slot therein through which said shaft extends, a slide mounted on said member and provided with substantially horizontally disposed spaced cross-pieces, a cam on said shaft adapted to engage said cross-pieces, means for operatively connecting said slide and said reciprocable member, said means including springs that permit the longitudinal movement of said reciprocable member independent of the slide.

6. A mechanical movement comprising a rotatable drive-shaft, a longitudinally reciprocable member having an elongated slot therein through which said shaft extends, a

- slide mounted on said member and provided with substantially horizontally disposed spaced cross-pieces, a cam on said shaft adapted to engage said cross-pieces, means for operatively connecting said slide and said reciprocable member consisting of a cross-arm carried by said reciprocable member, and a spring connecting said cross-arm to said slide.
- 10 7. A mechanical movement comprising a rotatable drive-shaft, a longitudinally reciprocable member having an elongated slot therein through which said shaft extends, a slide mounted on said member and provided with substantially horizontally disposed spaced cross-pieces, a cam on said shaft adapted to engage said cross-pieces, means for operatively connecting said slide and said reciprocable member, consisting of a lug projecting laterally from said reciprocable member and adapted to be engaged by one of said cross-pieces when the slide is moved in one direction, and springs connecting said reciprocable member to said slide and adapted to normally retain said lug in engagement with said cross-pieces.
- 15 8. A mechanical movement comprising a rotatable drive-shaft, a longitudinally reciprocable member having an elongated slot therein through which said shaft extends, a slide mounted on said member and provided with substantially horizontally disposed spaced cross-pieces, a cam on said shaft adapted to engage said cross-pieces, means for operatively connecting said slide and said reciprocable member, consisting of a lug projecting laterally from said reciprocable member and adapted to be engaged by one of said cross-pieces when the slide is moved in one direction, and springs connecting said reciprocable member to said slide and adapted to normally retain said lug in engagement with said cross-pieces.
- 20 9. A mechanical movement comprising a rotatable drive-shaft, a longitudinally reciprocable member having an elongated slot therein through which said shaft extends, a slide mounted on said member and provided with substantially horizontally disposed spaced cross-pieces, a cam on said shaft adapted to engage said cross-pieces when the slide is moved in one direction, a cross arm secured to and carried by said reciprocable members, and springs the lower ends of which are connected to said cross arm and the upper ends of which are connected to said slide.
- 25 10. A mechanical movement comprising a rotatable drive-shaft, a longitudinally reciprocable member having an elongated slot therein through which said shaft extends, a slide mounted on said member and provided with substantially horizontally disposed spaced cross-pieces, a cam on said shaft adapted to engage said cross-pieces, means for operatively connecting said slide and said reciprocable member, and devices adapted to actuate said reciprocable member independently of said cam and slide.
- 30 11. A mechanical movement comprising a rotatable drive-shaft, a longitudinally reciprocable member having an elongated slot therein through which said shaft extends, a slide mounted on said member and provided with substantially horizontally disposed spaced cross-pieces, a cam on said shaft adapted to engage said cross-pieces, means for operatively connecting said slide and said reciprocable member, consisting of a lug projecting laterally from said reciprocable member and adapted to be engaged by one of said cross-pieces when the slide is moved in one direction, and springs connecting said reciprocable member to said slide and adapted to normally retain said lug in engagement with said cross-pieces.
- 35 12. A mechanical movement comprising a rotatable drive-shaft, a longitudinally reciprocable member having an elongated slot therein through which said shaft extends, a slide mounted on said member and provided with substantially horizontally disposed spaced cross-pieces, a cam on said shaft adapted to engage said cross-pieces, means for operatively connecting said slide and said reciprocable member, consisting of a lug projecting laterally from said reciprocable member and adapted to be engaged by one of said cross-pieces when the slide is moved in one direction, and springs connecting said reciprocable member to said slide and adapted to normally retain said lug in engagement with said cross-pieces.
- 40 13. A mechanical movement comprising a rotatable drive-shaft, a longitudinally reciprocable member having an elongated slot therein through which said shaft extends, a slide mounted on said member and provided with substantially horizontally disposed spaced cross-pieces, a cam on said shaft adapted to engage said cross-pieces, means for operatively connecting said slide and said reciprocable member, consisting of a lug projecting laterally from said reciprocable member and adapted to be engaged by one of said cross-pieces when the slide is moved in one direction, a cross arm secured to and carried by said reciprocable members, and springs the lower ends of which are connected to said cross arm and the upper ends of which are connected to said slide.
- 45 14. A mechanical movement for shoe nailing machines comprising a vertically

reciprocable member, and means for reciprocating said member comprising a rotatable shaft, a cam carried thereby, a slide mounted on said member and actuated by said cam, and devices operatively connecting said slide and reciprocable member.

15. A mechanical movement for shoe nailing machines comprising a vertically reciprocable member, and means for reciprocating said member comprising a rotatable shaft, a cam carried thereby, a slide mounted on said member and actuated by said cam, devices operatively connecting said slide and reciprocable member, and means for reciprocating said member independently of said first-mentioned means.

16. A mechanical movement for shoe nailing machines comprising a vertically reciprocable member, and means for reciprocating said member comprising a rotatable shaft, a cam carried thereby, a slide mounted on said member and actuated by said cam, devices operatively connecting said slide and reciprocable member, and a manually operated lever for reciprocating said member independently of said means.

17. A mechanical movement for shoe nailing machines comprising a vertically reciprocable member, and means for reciprocating said member comprising a rotatable shaft, a cam carried thereby, a slide mounted on said member and actuated by said cam, devices operatively connecting said slide and reciprocable member, a foot lever fulcrumed at one end adjacent the lower end of said member, and a link operatively connecting said member to said foot lever.

18. A mechanical movement for shoe nailing machines comprising a vertically reciprocable member, and means for reciprocating said member comprising a rotatable shaft, a cam carried thereby, a slide mounted on said member and actuated by said cam, devices operatively connecting said slide and reciprocable member, a foot lever fulcrumed at one end below said member and provided with a transverse elongated slot, and a link one end of which is pivotally connected to the lower portion of said reciprocable member and the opposite end of which engages said slot.

19. A mechanical movement for shoe nailing machines comprising a vertically reciprocable member, and means for reciprocating said member comprising a rotatable shaft, a cam carried thereby, a slide mounted on said member and actuated by said cam, devices operatively connecting said slide and reciprocable member, a foot lever fulcrumed at one end below said member and provided with a transverse elongated slot, a link one end of which is pivotally connected to the lower portion of said reciprocable member and the opposite end of which engages said slot, at its upper end whereby the operation of said lever will actuate said reciprocable member independently of said drive shaft.

In testimony whereof I affix my signature in the presence of two witnesses.

MAURICE S. FINCH.
